UNITED STATES PATENT OFFICE.

FREDERICK C. DIVEN, OF SEATTLE, WASHINGTON.

CLIP AND SUPPORT FOR DISPLAY MATTER.

Application filed April 8, 1926. Serial No. 100,623.

My invention has particular reference to a wire device for detachably securing display matter to a circular surface of a metallic or glass container of merchandise; 5 and has for its chief object, the provision of a clip which will grip such a surface, and also afford integral compression elements designed to securely hold said matter in condition for proper display, and without dan- 10 ger of tilting.

In the accompanying drawing—

Figure 1 is a view, in perspective, of the device complete;

Fig. 2, a perspective also, showing the 15 device mounted on a bottle and holding a card for display; and,

Fig. 3, a top view of the same, the bottle and the arms of the device being shown in broken sections.

20 The device, preferably bent from a single piece of spring wire, consists, in the present embodiment, of a support having spaced and parallel side portions 1, a top portion 2, a diagonal portion 3, and an oppositely disposed diagonal portion 4; the bight portions 5, produced between the side and diagonal portions, providing spaced seats for a card, or the like, disposed within the support. The diagonal portion 3 is adapted 25 to contact with the adjacent side portion, but the diagonal portion 4, if desired, may be slightly spaced away from its adjacent side portion to facilitate the placing of display matter in the support.

30 A pair of outwardly rounded portions, denoted by 6, are formed by bending the free ends of the wire laterally of the support and slightly above the top portion thereof, the said rounded portions and the diagonal portions serving not only as guid- 35 ing and supporting parts but as movable compression elements useful in retaining display matter within the support, and as will be hereinafter more particularly described.

40 What I term a neck portion, designated by 7, is designed to project the support away from the outwardly curved sections of a pair of arms 8, which are disposed in about the same horizontal plane as said portion, and obviously are adapted to grip a 45 cylindrical section of a bottle or can. When the device is mounted on the neck of a bottle, as indicated in Fig. 2, the portion 7 permits the display matter to assume a 50 vertical position by spacing it away from said neck. In order that Fig. 3 may be

more easily understood, the container and display matter are designated as 9 and 10 respectively.

In operating the device, a card, for instance, is inserted within the support, the rounded portions 6 and the bends formed between the top and side portions acting as guideways for the card, and the bight portions 5, in cooperation with the other elements of the support, affording substantial means for securing the card therein. The clip is then mounted on the bottle so as to support the card either from the front or rear of the bottle, as desired, the spreading of the arms in embracing the bottle acting to direct the movable portions 3, 4 and 6 against the card interposed between them and the rigid portions 1 and 2 and produce a compressive effect upon it, thus securely holding the card in a vertical position. As will be apparent from an inspection of Fig. 3, the more the arms are spread the greater the compression on the card disposed within the support.

55 While the device is primarily intended for supporting display matter on cylindrical containers, it is useful also in supporting display matter on a counter, showcase, or the like. The said matter being placed in the support, as heretofore described, the arms 8 function as braces, which, in cooperation with the support will sustain a card of relatively large dimensions in a proper position for display. Under the construction of this device, the card also contributes support to itself, as the paper-retaining loops of the support permit the lower edge of the card, for a major portion of its length, to rest on the surface on which it 60 is displayed.

65 As it will be noted in Fig. 2, when the card is inserted within the support to its downward limit, the lower edge of the card is located below the level of the arms, hence 100 when the device is utilized as just described, the free ends of the arms, resting on a counter, for instance, will impart a slight backward slant to the display matter, and thus support the same in the most effective 105 manner for the purpose intended.

I claim:

70 1. A clip and support for display matter, comprising a length of wire bent to form a support having a top portion, a pair of side portions in spaced parallel relation and a pair of oppositely disposed diagonal por-

tions, and an outwardly bowed arm extending from each diagonal portion and in angular relation with the support, having a bend adjacent the top portion to afford guideways for the insertion of said matter within the support.

2. A clip and support for display matter, comprising a support having a frame, a pair of oppositely disposed diagonal portions extending within and slightly beyond the

frame, each having a rounded section adjacent an outer edge of the frame, said portions and sections defining compression elements for display matter carried by the support, and a resilient outwardly curved 15 arm extending from each rounded section on either side of and in angular relation with the support.

FREDERICK C. DIVEN.
